CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion with graphical user interface showing our new design;

FIG. 2 is a rear view of the portable terminal;

FIG. 3 is a left side view thereof;

FIG. 4 is a right side view thereof;

FIG. 5 is a top plan view thereof; and,

FIG. 6 is a bottom plan view thereof.

The broken lines outside the larger vertical rectangle shown in FIG. 1, and all the broken lines shown in FIGS. 2-6, show portions of the article, and form no part of the claimed design. The dashed broken lines of the larger vertical rectangle show the display screen, and form no part of the claimed design. The dash-and-dot broken lines of the smaller vertical rectangle represent a boundary of the graphical user interface, and form no part of the claimed design. The slashed lines show part of the graphical user interface, and form no part of the claimed design.
